ATTORNEY

UNITED STATES PATENT OFFICE.

JOSEPH M. LUCARELLE, OF BRIDGEPORT, CONNECTICUT, ASSIGNOR TO DICTAPHONE CORPORATION, OF BRIDGEPORT, CONNECTICUT, A CORPORATION OF NEW YORK.

PHONOGRAPH.

Application filed February 19, 1925. Serial No. 10,228.

This invention relates to phonographic machines, and in a more specific aspect to machines for recording or reproducing dictation, or both, such machines being known as commercial phonographs.

An object of this invention is to provide means, associated with the power-operated driving means of such machines, for mechanically performing functions heretofore performed by force extraneous to said driving means.

Another object is to provide means whereby the operation of said mechanical function-performing means may be manually controlled.

A further object is to provide means whereby said mechanical function-performing means may be manually controlled from a point remote from the machine.

And a still further object is to provide means whereby an operating part of said mechanical function-producing means may be manually operated at the will of the operator and independently of said power-operated driving means.

Another object is to provide a back-spacer mechanism for commercial phonographs which is operated by part of the machine which constantly operates while the machine is in use.

And yet another object is to provide a power-operated back-spacer and a control device therefor which is manually operable and mechanically actuated from a typewriting machine or other point remote from a phonograph.

And a still further object is to provide a power-operated back-spacer mechanism which may be applied to commercial phonographs as an attachment thereto.

Other objects and advantages will herein-after appear.

In the accompanying drawings which illustrate one form of the present invention as exemplary thereof—

Figure 1 is a front elevation of a dictation machine showing the present invention as embodied therein.

Fig. 2 is a perspective view of portion of the mechanism shown in Fig. 1, showing the parts in their operating positions.

Fig. 3 is a view similar to Fig. 1 showing

the parts in a position which they occupy when in position to be operated by the power-operated driving means of the machine and before they actually have been so operated.

Fig. 4 is a side elevation of the parts shown in Fig. 1 showing in full lines the normal inactive positions of the parts of this invention, and showing in dotted lines the positions which the parts assume when the device is manually caused to become effective.

Fig. 5 is a view similar to Fig. 4 but shows the parts in their operated positions.

While the commercial phonograph or dictation machine shown in the accompanying drawings is of the transcribing type, the invention is not limited to use in connection with this kind of a machine, but is also applicable to other machines such as dictating machines and combined dictating and transcribing machines, also other phonographs.

The machine shown comprises a base 10, containing a driving motor 11 and speed governing mechanism. The top of the casting is constituted by a table 12 having formed integral therewith a housing 13 for supporting a mandrel 14 adapted to carry a record 15 which is to be reproduced.

The table 12 also has vertical standards 16 and 17 between which there is mounted an upper guide rod 18 and a lower guide rod 19 adapted to control the travelling movements of a sound-box carriage 20 adapted to be moved over the record 15 to reproduce the sound recorded upon the record by the rotation of a feed-screw 21 which is engaged by a nut 22' mounted on the carriage 20.

The mandrel 14 is mounted upon a shaft on whose end a movable clutch member 22 is provided. This clutch member 22 is adapted to co-operate with a clutch member 23 secured to a pulley 24 which is constantly rotated while the machine is in use by the motor 11 through a belt 25. In using the machine, the clutch member 22 is moved into and out of engagement with the continuously operating clutch member 23 by the operator through mechanism not shown and of no consequence in connection with the

present invention. Suffice it to say, that even when the clutch member 22 is disengaged from the clutch member 23 the pulley 24 continues to operate, being at all times 5 positively driven through the belt 25 by the motor 11.

It frequently occurs in the use of the machine that the operator desires to revert to a portion of the record just passed to verify 10 the transcription or to again listen to something which was not entirely clear. To facilitate this, the machine is provided with a back-space mechanism comprising a key-lever 26 having a hub 27 carried by the 15 sound-box carriage 20 and upon which is mounted a pawl 28 adapted to co-operate with a tooth rack 29 supported upon the standards 16 and 17 directly above the upper guide rod 18.

20 When the back-space key-lever 26 is depressed the pawl 28 engages the rack 29 and forces the carriage backwardly i. e. toward the left, in Fig. 1. In operating, the back-space key-lever 26 also raises the nut 22' 25 from the feed-screw 21 to free the carriage therefrom for this back-spacing movement. It may or may not, as desired, raise the stylus from the record surface during this back-spacing movement, and so far as this invention 30 is concerned, it is immaterial whether it does or not.

For a more complete understanding of the back-space mechanism above described, attention is called to the patent to Macdonald 35 #1,030,740, June 25, 1912, fully disclosing the same.

Since the operator is usually some distance from the machine, receiving the sound from the sound-box 30 through a flexible tube 31, 40 it is sometimes inconvenient to reach over to the machine to operate the back-space key-lever 26. To avoid the necessity for doing this, the present invention provides means operated by the motor 11 for actually performing the back-spacing operation, this means being controlled from the type-writing machine or other point remote from the phonograph by an easily operated device, such as a Bowden wire.

50 In order that the device may be placed upon a phonograph as an attachment so it can be applied to existing machines, there is provided a main support 32 adapted to embrace the standard 16, or other convenient support, and to be secured thereto by screws 33 and an auxiliary support 34 adapted to embrace the standard 17, or other convenient support, and to be secured thereto by screws 35. These supports 32 and 33 each have 55 standing arms 36 rotatably supporting a transverse rod or shaft 37 in which is mounted a universal bar or vane 38 of such length and so positioned as to always be directly above and within contacting range 60 of the back-space key-lever 26, see Figs. 1, 4

and 5. The provision of the bail formed by the rod 37 and the vane 38 in this position, in itself constitutes a valuable feature, for when used alone without any operating mechanism, it permits the operator to actuate the back-space key-lever 26 by pressing directly upon the vane 38 at any point irrespective of the position of the carriage 20. Hence, it is not necessary for the operator to first locate the position of the key-lever 26 70 and then operate it, but may press the vane 38 anywhere in its length to obtain the same result.

However, in order that the vane may be automatically operated, the end of the rod 37 adjacent the pulley 24 is provided with a forked-lever 39 into which extends a pin 40 carried by an arm 41 pivotally mounted upon a screw 42 mounted in the standard 16. The arm 41 has coupled to it (by a pin 41^a) 80 for rotation upon the screw 42, a trip-lever 43 whose rear-end 44 is adapted to engage one or more cams 45 mounted upon the driving pulley 24, so that when the trip-lever 43 is in position to be engaged by the cams 45, its rear-end 44 is raised while the forward end is depressed. Through the coupling of the forward end of the trip-lever 43 with the lever 41, by the pin 41^a, the lever 41 is also rocked downwardly, carrying with it its pin 40 which rides in the forked-arm 39 and rocks the rod 37 clockwise, as seen in Figs. 2, 4 and 5. This operation causes the vane 38 to engage the top of the key-lever 26 and depress the latter which results in a back-spacing movement being imparted to the carriage 20 by the mechanism heretofore described.

If the trip-lever 43 were allowed to normally remain in position to be engaged by the cams 45, the rod 37 would oscillate continuously until the carriage reached its rear-most position, and, of course, this is not usually desired. Therefore, in order that the operation of the back-space mechanism may be intermittent and may be fully controlled by the operator, the trip-lever 43 is normally held in inoperative position, that shown in Fig. 1, by a control-lever 46 (see Figs. 4 and 5) pivoted upon a screw 47 secured in an ear 48 bent laterally from the support 32. Normally the control-lever 46 is held by a spring 46^a so that its upper end 49, which inclines laterally and constitutes a cam, engages a forwardly extending arm 50 of the trip-lever, and causes the rear end of the latter to be cammed to the right, as shown in Fig. 1, against the tension of a spring 51 interposed between it and the head of the pin 41^a so as to normally be out of range of the cams 45 on the pulley 24.

When it is desired to operate the back-space mechanism by the power of the machine transmitted to the pulley 24, the control lever 46 is manually operated as by the

depression of a key-lever 52 to remove the cam portion 49 of the control-lever from the arm 50 of the trip-lever. This allows the spring 51 to cause the end 44 of the trip-lever 5 to move into the path of the cams 45 so that, when the cams 45 reach the trip-lever, it will oscillate and through the mechanism above described cause the oscillation of the rod 37 and the consequent operation of the back-space key-lever 26.

When the control-lever 46 is operated, it is held in operated position until the trip-lever itself operates, by reason of the engagement of the control-lever with the forward end 52 of the arm 50, see Figs. 2 and 3. Then, when the trip-lever 43 is moved by one of the cams 45 and reaches the limit of its movement, the end 50 passes down beyond the cam surface 49 of the control lever 20 to allow the latter to move rearwardly to its normal position. The trip-lever, in returning to normal position, causes its end 50 to engage the cam portion 49 of the control-lever and this causes the rear end 44 of the 25 trip-lever to be cammed to its normal inoperative position shown in Fig. 1. The trip-lever 43 remains in its idle position until the control-lever 46 is again operated. The trip-lever and its connected parts, including 30 the vane 38 and rod 37, are returned to normal position by the spring 46^a, having one end secured in the control-lever 46 and its other end fastened in the trip-lever 43.

For the purpose of allowing the control-lever to be operated from a distance, the support 32 is provided with an opening into which there is screw-threaded a sleeve 53 of a Bowden-wire device 54 (see Fig. 4) so that the operating end 55 of the Bowden-wire is 35 in the path of an arm 56 bent laterally from the control-lever 46. When the Bowden-wire is operated, the control-lever is moved from the position shown in full lines in Fig. 4 to that shown in dotted lines, and this, as 40 above explained, allows the trip-lever to function.

By holding the control-lever 46 in depressed position, either by operation of the key 52 or the Bowden-wire 55, the cam-surface 49 thereof is held out of range of the end 50 of the trip-lever 43. Consequently, so long as this control-lever 46 is held in this 50 position, the cams 45 on the pulley 24, will continue to oscillate the vane 38 and cause the intermittent but continued operation of the back-space key-lever 26.

Hence, when the operator desires to return the carriage a large extent, the control-lever 46 is held in depressed position until 55 the carriage reaches the position desired.

It should be understood that in its broader aspects this invention is not limited to the idea of only operating the back-space mechanism by power, but also embraces the idea 60 of operating any part of the machine by the

power of the motor and under the control of the operator.

While one form of the invention has been described and illustrated in detail, it should be understood that the invention is not limited to this particular form but that variations and modifications may be made within the scope of the invention and portions of the improvements may be used without others.

Having thus fully described the invention, what is claimed as new, and for which it is desired to obtain Letters Patent, is:

1. In a phonograph, power means moving continuously while the phonograph is in use; means adapted to be manually operable 70 to control the phonograph; and manually controlled means operated by the continuously moving power means for operating said manually operable means by power.

2. In a phonograph, the combination of 80 a record-support; sound-reproducing means comprising a stylus adapted to track a record; power means adapted to drive said record-support; and means indirectly and intermittently actuated by said power means 90 to shift said stylus backwardly over the record-support towards the beginning of the record.

3. In a phonograph, the combination of 95 a record-support; sound-reproducing means comprising a stylus adapted to track a record; power means adapted to drive the record-support; and means indirectly and intermittently operated by said power means and manually made effective to shift the stylus backwardly over the record-support 100 towards the beginning of the record.

4. In a phonograph, the combination of 105 a record-support; sound-reproducing means comprising a stylus adapted to track a record; a source of power; means indirectly actuated through the medium of said source of power and adapted to move said stylus backwardly towards the beginning of the record; and means for controlling the operation of the last-named means, said source of power being normally and continuously capable of indirectly and intermittently actuating said means for moving said stylus, while the phonograph is in use.

5. In a phonograph, the combination of a 115 record-support; driving means therefor; a traveling carriage; mechanism for moving the carriage in an advancing direction; mechanism for moving the carriage a limited predetermined extent in a returning direction upon each operation; and means operated by the driving means for the record-support for actuating the mechanism moving the carriage in a returning direction.

6. In a phonograph, the combination of a 120 record-support; driving means therefor; a traveling carriage; mechanism for moving the carriage in an advancing direction; mechanism for back-spacing the carriage 125

- step by step; and means operated by said driving means for the record-support for actuating said mechanism for back-spacing the carriage.
- 5 7. In a phonograph, means moving continuously while the phonograph is in use; operable means on the phonograph to control the same; and a normally inoperative movement transmitting lever between said continuously moving means and said operable means through the movement of which lever the continuously movable means operates said phonograph controlling means.
- 10 8. In a phonograph, means moving continuously while the phonograph is in use; operable means on the phonograph to control the same; a normally inoperative movement transmitting lever between said continuously moving means and said operable means through the movement of which lever the continuously movable means operates said phonograph controlling means; and means manually operated for making said lever operative.
- 15 9. In a phonograph, means moving continuously while the phonograph is in use; operable means to control the phonograph; a normally inoperative interponent between said continuously moving means and said operable means through which the continuously movable means operates said phonograph controlling means; and means for automatically making said interponent inoperative after each operation thereof.
- 20 10. In a phonograph, means moving continuously while the phonograph is in use; operable means to control the phonograph; a normally inoperative interponent between said continuously moving means and said operable means through which the continuously movable means operates said phonograph controlling means; manually controlled means for causing the interponent to be operative; and means automatically operated for returning said interponent to inoperative position after each complete operation.
- 25 11. In a phonograph, means moving continuously while the phonograph is in use; operable means to control the phonograph; a normally inoperative movement transmitting lever between said continuously moving means and said operable means through the movement of which lever the continuously movable means operates said phonograph controlling means; manually controlled means for causing said lever to be operative; and means for operating said manually controlled means at a distance from the machine.
- 30 12. In a phonograph, means moving continuously while the phonograph is in use; operable means to control the phonograph; a normally inoperative movement transmitting lever between said continuously moving means and said operable means through the
- movement of which lever the continuously movable means operates said phonograph controlling means; manually controlled means for causing said lever to be operative; means for operating said manually operable means at a distance from the phonograph; and a Bowden-wire connection connected to said manually controlled means adapted to be operated from a point remote from the machine. 75
- 35 13. In a phonograph, means moving continuously while the phonograph is in use; means adapted to be operated to control the phonograph; and manually controlled means operated intermittently by the first-named means for operating the last-named means; and means for actuating said manually controlled means from a distance from the phonograph. 80
- 40 14. In a phonograph, the combination of a record-support; driving means therefor having cams; a traveling carriage; mechanism for moving the carriage in an advancing direction; mechanism for back-spacing the carriage; and means operated by the cams on said driving means for the record-support for actuating said mechanism for back-spacing the carriage. 85
- 45 15. In a phonograph, means moving continuously while the phonograph is in use; cams thereon; operable means to control the phonograph; and a normally inoperative interponent having a part operated by the cams of said continuously moving means and a part engaging said operable means by means of which interponent the continuously movable means operates said phonograph controlling means. 90
- 50 16. In a phonograph, means moving continuously while the phonograph is in use; cams thereon; operable means to control the phonograph; an interponent having a part operated by the cams but normally inoperative, and a part engaging said operable means by means of which interponent the continuously movable means operates said phonograph controlling means; and a cam for automatically making said interponent inoperative after each operation thereof. 100
- 55 17. In a phonograph, means moving continuously while the phonograph is in use; cams thereon; operable means to control the phonograph; an interponent having a part operated by said cams but normally inoperative, and a part engaging said operable means by means of which interponent the continuously movable means operates said phonograph controlling means; a manually operated trip for causing the interponent to be operatively moved to position to engage said cams; and means for automatically returning said interponent to inoperative position after each complete operation. 110
- 60 18. In a phonograph, the combination of a record-support; a pulley therefor; a cam 115
- 65

mounted on the pulley; a frame; an interponent fulcrumed on said frame and having a part adapted to be moved into the path of said cam and a part adapted to operate 5 mechanism of the phonograph; and means for moving said interponent into the path of said cams.

19. In a phonograph, the combination of a record-support; a pulley therefor; a cam 10 mounted on the pulley; a frame; an interponent fulcrumed on the frame and adapted to be moved into the path of said cam; means for moving the interponent into the path of said cams and a bail operated by 15 said interponent.

20. In a phonograph, the combination of a record-support; a pulley therefor; a cam mounted on the pulley; a frame; an interponent fulcrumed on said frame and having 20 a part adapted to be moved into the path of said cam; a lever pivoted on said frame and having a pin and slot connection with said interponent, said pin and slot connection permitting said interponent to fulcrum and 25 causing said lever to pivot with said interponent when the latter is operated by said cam; and means operated by said lever for actuating mechanism of the phonograph.

21. In a phonograph, the combination of a record-support; a pulley therefor; a cam 30 mounted on the pulley; a frame; an interponent fulcrumed on said frame and having a part adapted to be moved into the path of said cam; a lever pivoted on said frame and 35 having a pin and slot connection with said interponent, said pin and slot connection permitting said interponent to fulcrum and causing said lever to pivot with said interponent when the latter is operated by said cam; a back-spacer for the phonograph; and 40 means for inter-connecting the back-spacer and the lever whereby the latter operates when the interponent is rocked.

22. In combination, a frame; a sound-box 45 carriage adapted to travel to and fro on the frame; means for shifting the carriage backwardly a predetermined extent; said means comprising a key-lever mounted on and traveling with the carriage; and means 50 mounted on the frame and extending along the path of the carriage and adapted to operate the key-lever mounted on the carriage in any position of the latter within the range of its said movements, said means being 55 itself manually operable at any position along its length.

23. In combination, a frame; a sound-box carriage adapted to travel to and fro on the frame; means for moving the carriage backwardly a predetermined extent on said 60 frame, said means comprising a key-lever mounted on the carriage and traveling therewith; and a bail mounted on the frame and overlying the key-lever and adapted to operate the key-lever in any of its positions 65

within the range of its traveling movement, said bail comprising a manually operable part extending across the frame and adapted to be manually operated at any point within its range. 70

24. In combination; a frame; a carriage adapted to travel to and fro on the frame; means mounted on the carriage and adapted to cause the carriage to return a predetermined extent upon its operation; and means 75 mounted on the frame and adapted to operate the last-named means in any of its positions within the range of its traveling movement, said means comprising a manually operable part extending across the frame for 80 a distance substantially equal to that of the distance traveled by the carriage and being manually operable at any point within its length.

25. In combination, a frame; a sound-box 85 carriage adapted to travel to and fro on the frame; means for shifting the carriage backwardly a predetermined extent; a shaft mounted in said frame; and a plate carried by said shaft and adapted to operate the 90 means for shifting the carriage backwardly.

26. In combination, a frame; a sound-box carriage adapted to travel to and fro on the frame; back-space mechanism for said carriage comprising a key-lever; and a plate 95 mounted on said frame and normally overlying the key-lever and extending along the path of the carriage and adapted when manually operated at any point within its length to operate said key-lever irrespective of the 100 position of the carriage with respect of the frame.

27. In combination, a frame; a sound-box carriage adapted to travel to and fro on the frame; means for back-spacing the carriage 105 mounted on said carriage; and a universal bar mounted on said frame and adapted to operate the last-named means in any of its positions upon the frame.

28. In combination, a frame; a sound-box 110 carriage adapted to travel to and fro on the frame; means for shifting the carriage backwardly a predetermined extent; said means comprising a key-lever mounted on and traveling with the carriage; and means 115 mounted on the frame and adapted to operate the key-lever mounted on the carriage in any position of the latter within the range of its to and fro movement.

29. In combination, a frame; a sound-box 120 carriage adapted to travel to and fro on the frame; means for moving the carriage backwardly a predetermined extent on said frame, said means comprising a key-lever mounted on a carriage and traveling therewith; and a bail mounted on a frame and overlying the key-lever and adapted to operate the latter in any of its positions within the range of its traveling movement to and 125 fro on the frame. 130

30. In combination, a frame; a carriage adapted to travel to and fro on the frame; means mounted on the carriage and adapted to cause the carriage to return a predetermined extent upon its operation; and means mounted on the frame and adapted to operate the last-named means in any of its positions within the range of its traveling movement to and fro on the frame.
- 10 31. In combination, a frame; a carriage adapted to travel to and fro on the frame; means mounted on the carriage and adapted to cause the carriage to return a predetermined extent upon its operation; means mounted on the frame and adapted to operate the last-named means in any of its positions within the range of its traveling movement to and fro on the frame; and means for detachably holding the last-named means upon the frame in position to operate the first-named means.
- 15 32. In combination, a frame; a sound-box carriage mounted on the frame for to and fro movements; a back-spacer for moving the carriage backwardly step-by-step; manually operable means for actuating said back-spacer; and power operated means for actuating said back-spacer.
- 20 33. In combination, a frame; a sound-box carriage mounted on the frame for to and fro movements; a back-spacer for moving the sound-box carriage backwardly step-by-step; power means for operating said back-spacer and controlled from a point remote from the machine; and means at the machine for manually operating said back-spacer.
- 25 34. In combination, a frame; a sound-box carriage mounted for to and fro movements on the frame; a back-spacer for moving the sound-box carriage backwardly step-by-step; power means for operating said back-spacer and actuated from a point remote from the machine; and means for actuating said power means from a point at the machine.
- 30 35. In a phonograph, the combination of a frame; a carriage mounted on the frame for to and fro movements; intermittently operating mechanism for moving the carriage in a returning direction; and means under the control of the operator for causing

said mechanism to continuously operate to return the carriage.

36. In a phonograph, the combination of a frame; a carriage mounted on the frame for to and fro movements; manually-controlled intermittently-operating mechanism for returning the carriage; and power means for operating said mechanism.

37. In a phonograph, the combination of a frame; a carriage mounted on the frame for to and fro movements; a continuously moving member for operating the phonograph; and means operated by said continuously moving member for returning the carriage step-by-step.

38. In a phonograph, the combination of a record-support; driving means therefor; a traveling carriage; mechanism for moving the carriage in an advancing direction; mechanism comprising a pawl and ratchet teeth engaged thereby for moving the carriage a limited predetermined extent in returning direction upon each operation; and means operated by the driving means for the record-support for actuating the mechanism moving the carriage in a returning direction.

39. In a phonograph, means moving continuously while the phonograph is in use; a carriage; back spacing means for moving the carriage backwardly a limited predetermined extent at each operation; and an interponent between said continuously moving means and said back-spacing means through which the continuously moving means may operate said back-spacing means.

40. In a phonograph, the combination of a record-support; driving means therefor having operating devices; a traveling carriage; mechanism for moving the carriage in an advancing direction; mechanism for back-spacing the carriage; and means operated by said operating devices on said driving means for the record-support for actuating said mechanism for back-spacing the carriage.

Signed at Bridgeport, in the county of Fairfield, and State of Connecticut, this 18th day of Feb., 1925.

JOSEPH M. LUCARELLE.
